DESIGN FOR A VANITY CASE

Dora M. Gelberg, New York, N. Y.

Application July 12, 1940, Serial No. 93,583

Term of patent 7 years

To all whom it may concern:

Be it known that I, Dora M. Gelberg, a citizen of the United States of America, residing at New York, county and State of New York, have invented a new, original, and ornamental Design for a Vanity Case, of which the following is a specification, reference being made to the accompanying drawing, forming a part thereof.

Fig. 1 is a front view of a vanity case showing the design; and

Fig. 2 is a side view thereof.
This application is a continuation-in-part of application Ser. No. D-90,930, filed March 15, 1940.

I claim:

The ornamental design for a vanity case, substantially as shown.

DORA M. GELBERG.
